UNITED STATES PATENT OFFICE.

JOHN M. LEVIS, OF CHICAGO, ILLINOIS, ASSIGNOR TO ILLINOIS GLASS COMPANY, OF ALTON, ILLINOIS, A CORPORATION.

DESIGN FOR A FLASK.

No. 38,557.

Specification for Design.

Patented May 14, 1907.

Application filed March 11, 1907. Serial No. 361,872. Term of patent 14 years.

To all whom it may concern:

Be it known that I, JOHN M. LEVIS, a citizen of the United States, residing in Chicago, in the county of Cook and State of Illinois, have invented a new, original, and ornamental Design for Flasks.

The accompanying drawing, which is a perspective view, illustrates my new, original and ornamental design for flasks.

I claim:

The ornamental design for a flask as shown.

JOHN M. LEVIS.
